US00D988091S

(12) **United States Design Patent** (10) **Patent No.:** **US D988,091 S**
Bacher et al. (45) **Date of Patent:** **** Jun. 6, 2023**

(54) **EATING UTENSIL**

(71) Applicant: **MASONTOPS, INC.**, Toronto (CA)

(72) Inventors: **Michael Bacher**, Toronto (CA); **Philip Baron**, Toronto (CA); **Brett Molnar**, Toronto (CA)

(73) Assignee: **MASONTOPS IP HOLDINGS, INC.**, Toronto (CA)

(**) Term: **15 Years**

(21) Appl. No.: **29/799,869**

(22) Filed: **Jul. 16, 2021**

(51) LOC (14) Cl. **07-03**

(52) U.S. Cl.

USPC **D7/655**; D7/653; D7/654

(57) **CLAIM**

The ornamental design for an eating utensil, as shown and described.

DESCRIPTION

FIG. 1 is top and front perspective view of an eating utensil showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view;

FIG. 7 is a bottom plan view; and,

FIG. 8 is a bottom and rear perspective view thereof.

The dashed broken lines in the figures illustrate portions of the eating utensil that form no part of the claimed design.

1 Claim, 7 Drawing Sheets
